UNITED STATES PATENT OFFICE.

DWIGHT S. RICHARDSON, OF BROOKLYN, NEW YORK.

HOT-AIR FURNACE.

SPECIFICATION forming part of Letters Patent No. 412,860, dated October 15, 1889.

Application filed October 3, 1888. Serial No. 287,073. (No model.)

To all whom it may concern:

Be it known that I, DWIGHT S. RICHARDSON, a citizen of the United States, residing in the city of Brooklyn, in the county of 5 Kings, in the State of New York, have invented a new and Improved Hot-Air Furnace, of which the following is a correct description.

The invention relates to that class of air-10 heating furnaces which are surmounted or encircled by a radiator or heating-drum, such radiator or drum being ordinarily provided with a diaphragm or flue-plate, along both sides of which the products of combustion pass on their way to their point of 15 exit from the furnace, the function of such plate or diaphragm being to change the direction of the escaping heat-currents and to insure their retention within the radiator 20 until the greater portion of their calorific shall have been radiated into the warm-air chamber of the furnace for utilization.

Hitherto it has been found extremely difficult, in constructing and operating this class 25 of furnaces, to provide a diaphragm or flue-plate which would for any considerable period resist the destructive action of the volatile products of combustion, the only construction of heavy radiator which has proven at all 30 effective being that in which the diaphragm is cast with the body of the radiator, as provided in United States Patent No. 272,326, issued to me on the 13th of February, 1883. The radiator described in that patent has 35 been operated with satisfactory results in all situations in which a high degree of heat maintained continuously for a long period of time has been desirable. In some situations, however, it is frequently found desir- 40 able to produce within the warm-air chamber of the furnace more quickly than is practicable in using a radiator of thick cast metal a high degree of heat, and to maintain this quickly-heating and rapidly-radiat- 45 ing condition indefinitely; and for such purposes I have found that a radiator composed of sheet metal or of very thin cast metal, and provided with a diaphragm of fire-brick or of soapstone, is more effective than any 50 other of which I have knowledge.

In the drawings, Figure 1 represents a side elevation of a furnace provided with my improved radiator, portions being broken out of the wall thereof to show the direction of the smoke-currents in their passage through 55 the same. Fig. 2 represents a transverse vertical section in the line *w w* of Fig. 1. Fig. 3 represents a transverse vertical section of a radiator of modified form.

The ash-pit *a*, the fire-pot *a'*, and the combustion-chamber *a²* of the furnace A may be of any ordinary or approved construction. The body or exterior wall of the radiator *A'*, receiving the smoke and gases from the combustion-chamber and discharging the same 60 into the uptake, is composed either of sheet metal or of very thin cast metal. Upon the inner surface of its walls the radiator is provided, by preference, with a supporting-ledge, or with a series of brackets *a³*, upon or 65 against which rests the diaphragm or flue-plate *A²*, composed, as already explained, of fire-brick or other refractory material.

It will be understood that in the radiator represented in Fig. 3 the side walls are of 75 thin metal, while the top plate and the bottom plate are of heavy cast metal. The flue-plate or diaphragm being very thick, as shown, will absorb a large portion of the heat contained in the first-received smoke-currents, and when thus charged with calorific will be of nearly uniform temperature throughout, and will consequently be but slightly, if at all, affected by the disparity 80 in temperature between the incoming and outgoing smoke-currents, while the thinness of the metallic portion of the radiator will insure rapid heating of the contents of the surrounding air-chamber.

Having described my invention, I claim— 90

1. In an air-heating furnace, a radiator or heating-drum which is divided by a detachable diaphragm or flue-plate into an incoming and an outgoing flue, the body of the radiator being composed of thin quickly-radiating metal, and the diaphragm or flue-plate being composed of fire-brick or other analogous refractory material, substantially as and for the purposes set forth. 95

2. In an air-heating furnace, a radiator or 100

heating-drum which is divided by a detachable diaphragm into an incoming and an outgoing flue, the body of the radiator being composed of thin quickly-radiating metal,
5 the diaphragm being composed of fire-brick or like refractory material and serving to reverse the direction of the flow of the vola-

tile products of combustion, substantially as described.

DWIGHT S. RICHARDSON.
